UNITED STATES PATENT OFFICE.

HARMON E. COREY, OF LOS ANGELES, CALIFORNIA.

SPARK PLUG.

Application filed March 10, 1924. Serial No. 698,043.

To all whom it may concern:

Be it known that I, HARMON E. COREY, a citizen of the United States, residing at Los Angeles, in the county of Los Angeles and State of California, have invented new and useful Improvements in Spark Plugs, of which the following is a specification.

This invention relates to spark plugs and it has for one of its objects the provision 10 of a spark plug which will effect a more complete combustion of fuel in internal combustion engines.

Another object of this invention is the provision of a spark plug having a plurality 15 of spark gaps in series.

A further object of this invention is the provision of a spark plug capable of giving a more efficient spark.

With the foregoing objects in view, together with such other objects and advantages as may subsequently appear, my invention resides in the construction and arrangement of parts hereinafter described and claimed and illustrated in the accompanying drawings, in which:

Figure 1 is an elevational view, partly in section, of a spark plug embodying my invention, and

Fig. 2 is a bottom plan view of Fig. 1.

Referring to the drawings for a more detailed description thereof, the numeral 5 indicates a spark plug having the usual central electrode 6, the upper end of which is designated by 6^a. The spark plug 5 is of usual construction excepting only the electrode which cooperates with the central electrode 6 and the novel parts associated with the former electrode. The electrode which cooperates with the central electrode 6 is adapted as usual to be connected to a source of electric current and comprises two branches 7 and 8 respectively, the opposing ends of which are separated by a space 9. Insulating material 10 is placed around the end portions of the branches 7 and 8 and extends across the space 9. An electrical conductor 12 is placed on, and preferably

around, the insulating material 10, so that part of the conductor 12 is between the central electrode 6 and the other electrode comprising branches 7 and 8.

In the operation of this spark plug, a spark jumps from the electrode 6 to the conductor 12 and thence to the branch 7 or 8 of the other electrode. It will thus be seen that there is a plurality of spark gaps in series in the device of my invention and it is this feature that effects a more complete combustion of the gasoline or other fuel.

Furthermore, actual use of my device has shown that the sparks provided by my device are more efficient than the sparks provided by other spark plugs operating under the same conditions under which I have tested the spark plug of my invention.

I have thus provided a spark plug having a plurality of spark gaps in series and comprising two electrodes adapted to be connected to a source of electric current, insulating material on one of the electrodes, which preferably consists of two branches, and an electrical conductor around the insulating material, the electrical conductor being interposed in part between the two electrodes.

While I have herein described one form of my invention, modifications thereof may be devised without departing from the spirit thereof, and it is to be understood that such modifications come within the scope of this invention.

What is claimed is:

A spark plug having a central electrode, a pair of electrodes constituting a second electrode disposed beneath said central electrode and having opposed ends, a sleeve of insulating material mounted upon said opposed ends, and a sleeve of conducting material about said sleeve of insulating material, said conducting material being held in spaced relation to said central electrode.

In testimony whereof I have signed my name to this specification.

HARMON E. COREY.
